UNITED STATES PATENT OFFICE.

DUDLEY TYNG FISHER, JR., OF COLUMBUS, OHIO.

DESIGN FOR A STATUETTE.

Application filed October 3, 1925. Serial No. 15,019. Term of patent 14 years.

To all whom it may concern:

Be it known that I, DUDLEY TYNG FISHER, Jr., a citizen of the United States, residing at Columbus, in the county of Franklin and State of Ohio, have invented a new, original, and ornamental Design for a Statuette, of which the following is a specification, reference being had to the accompanying drawings, forming part thereof.

Fig. 1 is a rear perspective view and Fig. 2 is a front perspective view of the statuette.

I claim:

The ornamental design for a statuette as shown.
